(57)

CLAIM

The ornamental design for a display module, as shown and described.

DESCRIPTION

FIG. 1 is a front, right perspective view of the display module showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a rear, left perspective view thereof.

1 Claim, 8 Drawing Sheets(56)
